DRYING RACK

Robert H. Gilley, Norfolk, Va.

Substituted for abandoned application Serial No. 420,324, November 24, 1941. This application June 30, 1943, Serial No. 492,950

1 Claim. (Cl. 211—41)

This invention relates to new and useful improvements in racks on which work can dry and more particularly to a rack upon which freshly coated mirrors can be placed to dry and be protected against chipping or other damage, this being a substitute application predicated on abandoned application Serial No. 420,324, filed November 24, 1941, and which was allowed September 30, 1942.

The principal object of the present invention is to provide a rack of the character stated which can be assembled unit by unit as pieces of work are placed thereon.

Other objects and advantages of the invention will become apparent to the reader of the following specification.

In the drawings:

Figure 1 represents a side elevational view of a pile of rack units.

Figure 2 is a top plan view of one of the units.

Figure 3 is a bottom plan view of one of the units.

Figure 4 is a section on the line 4—4 of Figure 3.

Figure 5 is a section on the line 5—5 of Figure 3.

Figure 6 is a reduced perspective view showing one of the units without a fabric covering.

Referring to the drawings wherein like numerals designate like parts, it can be seen in Figure 1 that numeral 5 generally refers to a rack constructed of a plurality of units such as are shown in Figures 2 and 3. Each of these units is capable of holding one or more flat pieces of work such as newly silvered mirrors.

Each unit as constructed comprises a plurality

of parallel spaced slats 6 bridged at their ends by upper and lower runners 7 and 8. The ends of the slats 6 and the runners 7 and 8 are nailed as at 9 or otherwise secured together.

5 Numeral 10 denotes a sheet of fabric stretched over the slats 6 which affords a soft surface to prevent scratching of the mirror or other work.

Of course, this fabric sheet can be eliminated and the rack used in the form generally referred to by numeral 11 and shown in Figure 6.

10 The rack units are stacked one upon another as pieces of work A are placed in position. (See Figure 1.)

15 While the foregoing specification sets forth the invention in specific terms, it is to be understood that numerous changes in the shape, size and materials may be resorted to without departing from the spirit and scope of the invention as claimed hereinafter.

20 Having described the invention, what is claimed as new is:

25 In a drying rack for mirrors and the like, a stack of loosely piled, rectangular, mirror supporting units, each comprising a plurality of spaced parallel cross-slats, and pairs of side runners extending at right angles to the cross-slats, the cross-slats having the ends thereof interposed between and fixed to the runners of said pairs, and said pairs of runners being superposed upon each side of the stack and parallel, and a sheet of fabric material resting on the cross-slats of each unit and stretched thereon, said pairs of runners spacing the cross-slats and sheets of fabric of each unit apart.
